UNITED STATES PATENT OFFICE.

HOWARD D. RANDALL, OF CINCINNATI, OHIO.

FRICTIONAL-CONTACT WINDOW GUIDE.

Application filed December 6, 1927. Serial No. 238,022.

This improvement relates to an improved window channel and particularly to that type of channel intended for use with doors or windows of closed motor cars, such as with 5 sedans and in similar uses.

There are many essentials demanded by the trade of a window guide adapted to general automobile use. It must be capable of continuous use in all kinds of weather and must 10 not be affected injuriously by dust and must retain its attractive appearance under any or all these conditions and be capable of guiding the window without binding and to the best advantage. An additional requisite 15 is that the guide must be adapted to the usual and ordinary methods of assembly adopted by the trade, and it is almost a prime requisite that the guide device shall be such that one side can be held at right angles to the base 20 while the other side is held in line with the base so that the glass can be readily inserted and after the glass has been positioned the second mentioned side can be turned up into proper engaging position. This last 25 requisite has almost barred from general use a metal channel of any and all kinds since it is impossible to adapt it to the foregoing line assembly. Likewise, felt guiding devices are objectionable because dust and 30 water very quickly act injuriously upon the felt. It has long been recognized that it was desirable to devise a construction, retaining the advantage of the felt for the frictional contact with the glass, but having the metallic exterior effect, such as to maintain an attractive appearance and if necessary be washable while still being adapted to line assembly 35 method described above.

The invention described herein has all the 40 advantages just mentioned, a main feature being that the device has an outer flexible washable container and an inner felt contact member, the outer member having sides that can be manipulated to permit ready assembly of the glass and insertion within the rabbet in accordance with the practices mentioned above. The character of the outside cover is such and its particular relation to the inside felt member is such that it presents the 45 smoothness of the outside surfaces almost equal to a metal cover, while also presenting a maximum of flexibility for the side walls enabling it to be assembled with the glass to the greatest advantage.

55 Other objects and advantages will be in

part indicated in the following description and in part rendered apparent therefrom in connection with the annexed drawings.

To enable others skilled in the art so fully to apprehend the underlying features hereof 60 that they may embody the same in the various ways contemplated by this invention, drawings depicting a preferred typical construction have been annexed as a part of this disclosure and, in such drawings, like characters of reference denote corresponding parts 65 throughout all the views, of which:—

Figure 1 is a plan view of the window guide, Fig. 2 is a transverse sectional view and Fig. 70 3 is a perspective view showing the sides bent up to proper holding position.

Referring to the drawings, the outer covering or container is marked 1; the inner felt member is marked 2; the stitches for securing the felt to the outer covering are marked 3; the reinforcing strands for the outer edges 75 of the cover or container are marked 4. There is preferably employed a paper strip 5 placed between the felt and the outer covering for the purpose of assisting in the bending of the 80 sides of the guide.

The outside cover is imitation leather and as shown in Figs. 2 and 3 is of a thin character such that it can be combined most advantageously with the interior thick felt 85 contact member 2. The outer container 1 has its thin edges extended beyond the edges of the felt (Fig. 2) and the edges of the container are bent back upon themselves in a way to form openings for the strands 4, 90 and when the sides of the container are bent into proper holding position these strands 4 hug closely the top surface of the felt as indicated in Fig. 3. Moreover, the thin character of the imitation leather container is 95 such that it is only necessary to stitch the felt to said container by two lines of stitches marked 3 to enable the felt and cover to be bent into channel form, thus avoiding the trouble and expense of cutting out grooves 100 in the felt or forming the felt into strips spaced apart to form grooves. The inserted paper strip 5 is not essential to the operation of this device, but it may be used to assist as a straight edge for bending the sides of 105 the felt and cover to form a channel.

In this way there is presented a frictional contact guide or channel, wherein there is a flexible washable cover capable of containing the thick felt member, and stitched to 110

gether in a way to enable the parts to be adapted to the commonly used line assembly method.

The complete device presents somewhat the 5 appearance of and the advantages of a device having metallic sides; for the coating on the imitation member 1 is a film giving to the outside surface of the leather a glazed or glossy effect and yet the thinness of the 10 container adapts it admirably to the character of a channel having bent up sides and to remove the injurious effects of rain and dust, it will only be necessary to wash the outside surfaces of the imitation leather.

15 Without further analysis, the foregoing will so fully reveal the gist of this invention that others can, by applying current knowledge, readily adapt it for various utilizations by retaining one or more of the features that, from the standpoint of the prior 20 art, fairly constitute essential characteristics of either the generic or specific aspects of this invention and, therefore, such adaptations should be, and are intended to be, comprehended within the meaning and range of 25 equivalency of the following claims.

Having thus revealed this invention, I claim as new and desire to secure the following combinations and elements, or equivalents thereof, by Letters Patent of United 30 States:—

1. In a frictional contact guide the combination of a contacting felt member with an outer covering of a washable character, a 35 plurality of lines of stitches for connecting the felt member and covering together, said lines of stitches forming the sole means for marking the lines upon which the sides of felt and outer casing are bent up from the 40 body portion thereof to form the guide.
2. As an article of manufacture a frictional contact guide made entirely of fabric comprising a thin outer covering of washable material, an inner felt member extending 45 substantially from one edge of the outer cover to the other edge of substantially uniform thickness throughout, secured to said

outer covering by rows of longitudinal stitches forming said felt into three portions of substantially the same thickness, and 50 of such character that the side portions can be folded upon the central portions; the lines of stitches acting as hinges to permit the parts to be folded into channel form.

3. As an article of manufacture a frictional contact guide made entirely of fabric comprising a thin outer covering of washable material, an inner felt member extending substantially from one edge of the outer cover to the other edge of substantially uniform thickness throughout, secured to said outer covering by rows of longitudinal stitches forming said felt into three portions of substantially the same thickness, and of 60 such character that the side portions can be folded upon the central portions, the lines of 65 stitches acting as hinges to permit the parts to be folded into channel form, re-enforcing strands for the outer edges of the outer covering and lying above the felt member when 70 the parts are formed into channel form.

4. As an article of manufacture a frictional contact guide made entirely of fabric comprising a thin outer covering of washable material, an inner felt member extending substantially from one edge of the outer cover to the other edge of substantially uniform thickness throughout, secured to said outer covering by rows of longitudinal stitches forming said felt into three portions of substantially the same thickness, and 80 of such character that the side portions can be folded upon the central portions, the lines of 85 stitches acting as hinges to permit the parts to be folded into channel form, re-enforcing strands for the outer edges of the outer covering and lying above the felt member when 90 the parts are formed into channel form, an insertable member between the lines of stitches for forming straight edges for the bending operation.

In witness whereof, I hereunto subscribe my name.

HOWARD D. RANDALL.
